UNITED STATES PATENT OFFICE

HARRY V. BALL, OF CONCORD, MASSACHUSETTS, AND WALTER OGDEN, OF CLEVELAND, OHIO, ASSIGNORS TO R. HOE & CO., INC., OF NEW YORK, N. Y., A CORPORATION OF NEW YORK

WEB ROLL CHANGER

Application filed August 17, 1925. Serial No. 50,536.

This invention relates to certain improvements in roll changers for printing machines and methods of controlling the web tension in these roll changers.

5 It is the especial object of the invention to provide an improved web roll changer and a tension controlling device for the web roll running to the printing press by which the desired tension can be put on the running roll, and the expiring web readily and easily joined or pasted to a spare roll, the tension device acting to provide the desired web control as the roll decreases in size.

10 It is a further object of the invention to provide an improved roll changer which is capacitated to carry a plurality of web rolls, such as a running roll and a spare roll, which may be manipulated to bring the spare roll into position to be conveniently joined to an expiring web and then into engagement with the tension controlling device.

15 It is a further object of the invention to provide means for simply and easily adjusting the surface tension exerted by the web controlling device on the roll.

20 With these and other objects not specifically referred to, the invention consists in certain novel parts, arrangements and combinations which will be described in connection with the accompanying drawings and the novel features pointed out in the claims hereunto annexed.

25 The drawings show, diagrammatically, a roll changer embodying the invention, and in these drawings—

30 Figure 1 is a side elevation of a roll support capacitated to carry two rolls, the parts being shown in the position they occupy when a spare roll is being loaded on the support;

35 Figure 2 is a similar view showing the parts in the position they occupy when running; and

40 Figure 3 is a similar view showing the parts in the position they occupy after a spare roll has been joined in the running web and before the parts are moved to the position shown in Figure 1.

45 Referring now to these drawings, the invention has been illustrated in connection with a roll support capacitated to hold two

rolls, a running roll indicated by the letter R and a spare roll indicated by the letter S. The roll support, of course, may take widely different forms. In the particular construction shown, the roll support is in the form of a pair of straight arms, one of which is shown, marked 1, centrally mounted on each end of shaft 2. The ends of these arms are provided with bearings 3, 4, in which are supported the running roll R and spare roll S. 55 These arms, it will be observed, extend on each side of the shaft 2. The rolls may be loaded into the support in any suitable manner as from a truck indicated by 5 in Figure 1.

60 Arranged conveniently adjacent this support, so as to engage a roll carried therein, is the improved tension controlling device. This tension controlling device is of such character as to yieldingly engage the roll and may conveniently take the form of belts or blankets 6. In constructions embodying the invention, where blankets or belts are employed, one end of the belt or blanket is fixed so that it has no traveling movement and, in the construction shown, the fixed point is 65 located outside or away from the roll support. As shown, the lower end of the blanket is fixed to a support 14 hereinafter referred to. 70

75 In this instance the upper end of the controlling device is free to move so that it will follow up the roll with the desired tension. While various means may be provided for thus supporting the free end of the blanket, in the particular construction shown the blanket passes over a pair of guide rolls 9, 80 10, and is yieldingly held in contact with the roll surface by means of a weight W. In the best construction this weight is adjustable so that the degree of tension exerted by the blanket on the roll surface may be varied 85 as desired. With this end in view, the weight is divided into several sections 11 secured on a rod 12 to which the free end 13 of the blanket is secured.

90 While the support to which the end of the blanket is fixed may be varied, as shown, it is fixed to a roll 14 which is preferably carried on a pivoted arm 15, as indicated at 16. This arm is proportioned so that, with a full web roll, the roll 14 is located at a point in advance 95

of the vertical axis of the roll so that the blanket is caused to hug the surface of the roll for a large portion of its periphery. From the roll the web marked X goes to the 5 press, not shown, through the usual draw-off rolls 17, 18.

The support is rotatable by any suitable means, not shown. In the operation of the 10 device a roll is loaded into the support and the web threaded into the press and the support then rotated, as shown in Figure 1, and the running roll is brought under control of the blanket. A spare roll may now be loaded into the support and when this is done the 15 support is further rotated to the running position shown in Figure 2. As the running roll decreases in size, the pull of the weight holds the blanket in close contact with the periphery of the roll. It will be observed that as the roll decreases in size the hug of the blanket decreases, that is, engages less of the roll surface so that the tension on the roll is kept uniform during the run. After the 20 running roll has practically expired, the support may be rotated so as to bring the spare roll conveniently adjacent the web. At this time the press may be stopped and the expiring web joined to the spare roll by the pressman. If desired, the support may be 25 rotated to press the new roll against the web and belt and thus paste them together while the press is running, the rotation of the new roll being started by hand. The support is then further rotated to discharge the expired 30 roll spindle and to bring the spare roll, now the running roll, into contact with the belt. The parts are then further rotated to the 35 position shown in Figure 1, another spare loaded into the support, and the support then moved to the running position shown in 40 Figure 2, this operation being repeated as long as the press is operated. It will be seen from the above that the new roll is rotated against the fixed belt and the belt is held at a 45 point by means of a pivoted guide which is inside the arc of rotation of the roll support. With this method of operating, the spare roll may be quickly and easily joined to an expiring web, it being understood that paste or 50 other suitable adhesive is applied to a portion of the spare roll before pasting, and the web and the spare roll are pressed together. By the use of the fixed belt against which the roll is moved a good control of the web is 55 obtained, and the web fed into the press under the required constant tension. It will also be observed that by leaving one end of the belts free, and providing the free ends with suitable tensioning means, as the 60 weights, the pull exerted on the belts is in the same direction as the rotation of the roll. This has the effect of producing a good engagement of the belts with the roll surface. 65 While the invention has been shown and described in a preferred and practical form,

it will be understood, of course, that various changes in the arrangement and the structure of the web controlling device may be made without departing from the invention as defined in the appended claims.

70

What is claimed is:

1. In a roll changer, the combination of a running web roll and a spare web roll supported to rotate from loading position to running position, a belt or the like engaging the surface of the running roll throughout its unwinding and arranged to engage the spare roll when moved into running position, said belt being stationary relatively to the rotation of the roll, and a movable support arranged to be moved out of the path of the roll when the rotary support is rotated for fastening one end of the belt at a point independent of the roll support, the other end of the belt being free to maintain the belt under tension and the belt following the roll as it decreases in size, and tensioning means connected with the free end of the belt.

75

2. In a roll changer, the combination of a running web roll and a spare web roll supported to move from loading position to running position, a belt or the like engaging the surface of the running roll throughout its unwinding and arranged to engage the spare roll when moved into running position, said belt being stationary relatively to the rotation of the roll, a movable support for fastening one end of the belt at a point independent of the roll support, the other end of the belt being free to maintain the belt under tension and the belt following the roll as it decreases in size, guides over which the free end of the belt runs, and a weight secured to the free end of the belt.

80

3. In a roll changer, the combination of a running web roll and a spare roll supported to move from loading position to running position, a belt or the like engaging the surface of the running roll throughout its unwinding and arranged to engage the spare roll when moved into running position, said belt being stationary relatively to the rotation of the roll, a pivoted support carrying one end of the belt and mounted at a point independent of the roll support, the other end of the belt being free to maintain the belt under tension and the belt following the roll as it decreases in size, guides over which the free end of the belt runs, and a weight secured to the free end of the belt.

90

4. In a roll changer, the combination of a running web roll and a spare roll, arms in which the rolls are supported, a shaft for the arms rotatable to move the web roll from loading position to running position and from running position to discharging position and into the rotating position, a belt or the like engaging the surface of the running roll throughout its unwinding and arranged to

engage the spare roll when moved into running position, said belt extending under the roll and being stationary relatively to the rotation of the roll, a pivoted support arranged to be moved out of the path of the roll when the rotary support is rotated carrying one end of the belt and mounted at a point independent of the roll support, and means for maintaining the belt under tension.

5. In a roll changer, the combination of a running web roll and a spare roll, arms in which the rolls are supported, a shaft for the arms rotatable to move the web roll from loading position to running position and from running position to discharging position and then to rotating position, a belt or the like engaging the surface of the running roll throughout its unwinding and arranged to engage the spare roll when moved into running position, said belt extending under the roll and being stationary relatively to the rotation of the roll, a pivoted support carrying one end of the belt and mounted at a point independent of the roll support, guides over which the other end of the belt passes, and a weight secured to said other end of the belt.

6. In a roll changer, the combination of a running web roll and a spare web roll, a rotary carrier in which the rolls are mounted arranged to move from loading position to running position, a belt or the like engaging the surface of the running roll throughout its unwinding and arranged to engage the spare roll when rotated into running position, said belt being stationary relatively to the rotation of the roll, means arranged to be moved out of the path of the roll when the carrier is rotated for fastening one end of the belt at a point independent of and at a point below the roll support, the other end of the belt being free to maintain the belt under tension and the belt following the roll as it decreases in size, and tensioning means connected with the free end of the belt.

7. In a roll changer, the combination of a running web roll and a spare roll supported to move from loading position to running position, a belt or the like engaging the surface of the running roll throughout its unwinding and arranged to engage the spare roll when moved into running position, said belt being stationary relatively to the rotation of the roll, means arranged to be moved out of the path of the roll when the support is moved for fastening one end of the belt at a point independent of the roll support and at the side of the vertical axis of the running roll opposite the unwinding web, and means for maintaining the belt under tension.

8. In a roll changer, the combination of a running web roll and a spare web roll, a rotary carrier for supporting the rolls and

arranged to rotate from loading position to running position, a belt or the like engaging the surface of the running roll throughout its unwinding and arranged to engage the spare roll when rotated into running position, said belt being stationary relatively to the rotation of the roll, means arranged to be moved out of the path of the roll when the carrier is rotated for fastening one end of the belt at a point independent of the roll support and at the side of the vertical axis of the running roll opposite the unwinding web, and means for maintaining the belt under tension.

9. The method of effecting a change of web rolls in a press which consists in supporting a running web roll and a spare roll so that the running roll may engage a belt or the like throughout its unwinding, which belt is fixed at a point independent of the support and to one side of the vertical axis of the running roll opposite the unwinding web, said belt being under a constant tension to tension the web, moving the spare roll into pasting position and pasting the web and a spare roll together, and moving the new running roll into running position, and the belt support being arranged to be moved out of the path of the running roll when the spare roll is moved into pasting position.

10. In a roll changer, the combination of a running web roll and a spare web roll and a support therefor arranged to move from loading position to running position, a belt engaging the surface of the running roll as it unwinds, means at a point below the roll support for fastening one end of the belt and arranged to be moved out of the path of the roll when the support is rotated, the other end being free, and tensioning means secured to the free end of the belt and exerting a pull thereon in the direction of the run of the unwinding web.

11. In a roll changer the combination with a rotary support capacitated to support a spare roll and a running roll, a belt engaging the surface of the running roll, and a pivoted support to which one end of the belt is secured located well to one side of the vertical axis of the roll in running position so as to provide a wide area of contact of the belt on the running roll and arranged to be moved out of the path of the roll when the support is rotated.

12. In a roll changer the combination of a rotary support capacitated to support a spare roll and a running roll, a belt engaging the surface of the running roll, a movable support to which one end of the belt is fast located well to one side of the vertical axis of the roll in running position so as to provide a wide area of contact of the belt on the running roll and arranged to be moved out of the path of the roll when the support is rotated, the other end of the belt being free.

to maintain the belt under tension, and the belt following the roll as it decreases in size, and tensioning means connected with the free end of the belt.

5 13. In a roll changer the combination with a rotary support capacitated to support a spare roll and a running roll, a flexible friction device engaging the surface of the running roll, and a support to which one end of
10 the flexible friction device is secured, which support is located well to one side of the vertical axis of the roll in running position so as to provide a wide area of contact of the belt on the running roll and arranged to be
15 moved out of the path of the roll when the support is rotated.

14. In a roll changer, the combination of a rotary support capacitated to support a spare roll and a running roll, a flexible friction device engaging the surface of the running roll, and a support to which one end of the flexible friction device is secured, said device support being normally within the space through which the web roll passes when the rotary
25 support is turned.

15. In a roll changer, the combination of a rotary support capacitated to support a spare roll and a running roll, a flexible friction device engaging the surface of the running roll,
30 and a support to which one end of the flexible friction device is secured, said device support being normally within the space through which the web roll passes when the rotary support is turned and movable out of said
35 space by the pressure of the web roll.

16. In a roll changer, a rotatable web roll carrier adapted to carry a spare web roll and a running web roll, a tension device including a belt support therefor, said support being
40 located within the space through which the web rolls pass when the carrier is rotated, and a belt engaging the surface of the running roll and having one end fastened to the belt support and the other end held yieldingly
45 under tension.

In witness whereof, we have hereunto set
our hands.

HARRY V. BALL.
WALTER OGDEN.
